UNITED STATES PATENT OFFICE.

CLARK H. CARMER, OF WILLIAMSVILLE, NEW YORK.

TELEPHONE-RECEIVER SUPPORT.

Application filed May 15, 1925. Serial No. 30,554.

The present invention relates to telephone supports and particularly to supports for the receiver.

An object of this invention is to provide a device which may be detachably secured to an ordinary telephone instrument of the desk type, and which will hold the receiving member of the telephone in elevated position so as to permit the free use of both hands by the person using the instrument.

Another object of this invention is to provide a device which embodies the minimum number of parts, all of which may be lightly constructed and may be made of strap and sheet metal.

A further object of this invention is to provide a device which will not add materially to the weight of the instrument and will not interfere with the free use thereof.

The above and various other objects and advantages of this invention will in part be described in, and in part be understood from the following detailed description of the present preferred embodiment, the same being illustrated in the accompanying drawings, wherein:

Fig. 1 is a detail perspective view of a telephone ordinarily referred to as a desk telephone, and having a device constructed according to the present invention secured thereto, the receiver being mounted upon the hook of the telephone so as to disengage the instrument from the central source of energy.

Fig. 2 is a fragmentary detail perspective view of the same and showing the device in operative position.

Fig. 3 is a transverse section taken through substantially the center of one of the spring clasps which engage the receiver.

Fig. 4 is a fragmentary detail side elevation of the receiver supporting member.

Fig. 5 is a transverse section taken substantially on the line 5—5 of Fig. 2.

Fig. 6 is an enlarged transverse section taken substantially on the line 6—6 and looking in the direction of the arrows, and

Fig. 7 is a top plan view of the base or supporting member of the device.

Referring to the drawings, 10 designates a telephone instrument of the ordinary type and which is usually designated as a desk telephone, having an enlarged base 11 and the usual receiver hook 12 upon which the receiver 13 is adapted to rest when the telephone is not in use. A base plate 14 is adapted to be secured to the bottom 11 of the tele-

phone instrument, and is substantially of the configuration of the base 11. The plate 14 has a plurality of upstanding clasps 15 which are adapted to extend over the base 11 of the telephone and bind the plate 14 upon the telephone. A locking or set screw 16 may be threaded into one or more of the clasps 15 adjacent the upper ends thereof so that when the screws are turned inwardly the inner end 60 thereof will extend over the upper portion of the base 11 as shown in Fig. 1. These locking screws 16 securely hold the base plate 14 against the bottom of the telephone instrument. 70

A foot or supporting member 17 is secured to the plate 14 and extends outwardly therefrom, and is bent upwardly as shown at 18 so that the outer end of the foot 17 is parallel with the plate 14 but rises slightly above the same. A receiver support or arm 19 is detachably mounted upon the outer end of the foot 17, and is secured thereto by a bolt 20 or the like. A cupped or box washer 21 is preferably mounted over the lower end of the arm 19, and the head of the bolt 20 is adapted to bind the washer 21 against the lower end of the arm 19 so as to hold the latter in adjusted position. The head of the bolt 20 is preferably knurled so that it may be readily tightened or loosened by the fingers and the arm 19 adjusted to the desired position. 80

A receiver arm 22 is pivotally mounted upon the upper end of the arm 19, being secured thereto by a thumb bolt 23, and a stop 24 is interposed between the bolt 23 and the outer sides of the arms 19 and 22 so that the arm 22 may be held in raised position as shown in Fig. 2. The stop 24 preferably comprises a U-shaped strap having its closed end or bight portion mounted upon the outer edges of the arms 19 and 22. The pin or bolt 23 not only holds the two ends of the arms 19 and 22 together, but also holds the strap 24 in position so that the arm 22 cannot fall backwardly. 90

The outer end of the arm 22 is preferably bent at right angles thereto as shown at 25, and a pair of spring clasps 26 and 27 are mounted upon the angular portion of the arm 22 in spaced relation to each other. The spring clasps 26 and 27 are adapted to detachably hold the receiver 13 upon the upper end 25 of the arm 22, so that when the arm 22 is swung upwardly the receiver 13 is carried therewith. A gasket 28 may be interposed 100 between the inner sides of the clamps 26 and 110

27 and the periphery of the receiver 13 so as to prevent lateral or circumferential movement of the receiver.

5 In the operation of this device, the base plate 14 is mounted upon the bottom of a telephone instrument and is fastened thereto by turning the screws 16 inwardly. The gaskets 28 are placed upon the receiver 13, and the spring clamps 26 and 27 may then be clamped 10 in position. Normally the arm 22 is positioned at substantially right angle to the supporting arm 19, and in this position the receiver 13 rests upon the hook 12. When it is desired to use the telephone, the receiver is 15 moved upwardly and is held in raised position by the stop 24 as shown in Fig. 2. In this position the ear of the operator may be lightly pressed against the receiver 13, and the telephone may then be used in the usual 20 manner. It will be seen from the foregoing that the user of the instrument need only use his hand to raise the receiver 13 from the hook 12 into upright position. The hand may then be removed from the instrument and both 25 hands may then be used for the transaction of business. When the conversation has been completed the arm 22 may be moved for-

wardly and downwardly, and the receiver 13 placed upon the hook 12 as shown in Fig. 1.

It is, of course, understood that various 30 changes and modifications may be made in the details of construction and design of the above specifically described embodiment of the invention without departing from the spirit thereof, such changes and modifications 35 being restricted only by the scope of the following claim.

What is claimed is:

In a support for the receiver of a portable telephone, the combination of a sheet metal 40 base including a main body portion of substantially the configuration of the telephone base, and a foot extending forwardly from and in the same plane as said body portion, said foot having its end raised and offset from the main body portion of the base, and in a horizontal plane parallel thereto, an upright receiver supporting arm having its lower end bent in angular relation to the main body portion and engaging upon said offset end of 45 said foot, and a bolt extending thru the lower end of the arm and said offset portion of said foot; adjustably securing the arm to said base.

CLARK H. CARMER.
